CLAIM

The ornamental design for a display tray for eyeglasses, sunglasses, or like eyewear, as shown and described.

DESCRIPTION

FIG. 1 is a perspective view of an embodiment of a display tray for eyeglasses, sunglasses, or like eyewear showing my new design;

FIG. 2 is a top plan view thereof;

FIG. 3 is a bottom plan view thereof;

FIG. 4 is a front elevation view thereof;

FIG. 5 is a rear elevation view thereof; and

FIG. 6 is a left side elevation view thereof, the right side elevation view being a mirror image thereof;

FIG. 7 is another perspective view thereof, shown with a pair of eyeglasses and a pair of clip-on sunglasses; and,

FIG. 8 is an enlarged portion of the perspective view of FIG. 1.

The broken lines immediately adjacent shaded areas represent bounds of the claimed design and environment while all other broken lines are directed to environment and are for illustrative purposes only. The broken lines form no part of the claimed design.
